UNITED STATES PATENT OFFICE.

FRANK EIDEN, OF REDDING, CALIFORNIA.

OIL CUP.

Application filed December 18, 1925. Serial No. 76,252.

The invention relates to certain new and useful improvements in oil cups and has for its object to provide certain new and useful improvements in the type of oil cup illustrated in my application for patent Serial No. 19,518, filed March 30, 1925.

In its more detailed nature the invention seeks to provide an improved oil cup closure 10 cups of the type stated, the said cap being of a simple spring hinged nature in which is provided means for overcoming the tendency of oil leakage when oil is forced up through the central tube of the cup by air 15 pressure, the said cap being provided with means for causing all oil thus directed to be positively returned into the oil cup chamber without possibility of leakage.

With the above and other objects in view 20 the invention further resides in the novel details of construction, combination and arrangement of parts, all of which will be first fully described in the following detailed description, then be particularly 25 pointed out in the appended claim and illustrated in the accompanying drawing in which:

Figure 1 is an enlarged central vertical section of an oil cup embodying my invention, the closure cap being shown as closed in full lines and open in dotted lines.

Figure 2 is a plan view of the oil cup embodying the invention.

In the drawing, in which like reference 35 numerals indicate like parts in all of the figures, 1 indicates the oil cup proper which includes the main oil receiving chamber 2, an externally threaded neck 3 whereby the same may be mounted for use, and an internally threaded oil discharge passage 4.

The passage 4 is counterbored as at 5 to provide an oil well, and a tube 6, threaded at its other end, is provided and is adapted to be threaded into the passage 4 in the manner illustrated in Figure 1 of the drawing. 45 The counterbore 5 providing an annular oil well surrounding the lower end of the said tube, and for providing communication from the said well through the wall of the tube 50 and into the discharge passage the said tube is provided with apertures 7, as indicated. The upper end 8 of the tube 6 projects approximately to the top of the oil cup and is notched to accommodate a screw driver or 55 other suitable tool by the use of which the tube may be screwed home.

A disk 9 is secured to the tube in any suitable manner to move longitudinally therewith and a filter packer 10 is interposed between the said disk and the bottom of the oil cup above the well 5 and apertures 7.

Thus, oil filled into the main chamber of the cup around the tube 6 is filter-fed through the packer 10, well 5 and holes 7 into and through the discharge passage 4 to the part or parts to be lubricated. As described in my previous application referred to, by rotating the tube 6 the density of the packer 10 may be varied and the feeding of oil from the main chamber through the passage 4 thus regulated to a nicety. As also described in that application, oil may be freely injected directly to the parts to be lubricated through the upper end of the tube, an unobstructed passage all the way through that tube being provided.

The parts thus far described are substantially the same as those described in my previous application referred to and no claim is made to that structure, per se.

As described, my improved oil cup is especially adaptable to use upon shock absorbers or like devices where the oil passages are subjected to air pressure and suction, the filter-feeding devices preventing an overcharge of oil by suction and the free passage through the central tube providing for free air escape without forcefully ejecting oil from the cup, as would be the case when using the ordinary type of oil cup.

It has been found, however, that even with my improved arrangement it is possible at remote times that air under pressure would be forced through the tube 6 just as a quantity of oil was trickling therethrough, with the result that the oil particles would be forced upwardly through the tube and at times leak out laterally from under the valve closure cap.

Therefore, in order to positively overcome all tendency to leak oil by air pressure action and to provide a simple closure cap whereby free access to the central tube 6 and main oil chamber 2 may be had I provide a flat closure cap 11 having down-turned edges just outside of the wall of the cup 1 and being spring-hinge connected as at 12 to one side wall of the said cup to permit full opening and exposure of the whole of the main oil chamber 2 in the manner indicated in dotted lines in Figure 1 of the drawing.

A collar 13 is secured to the inside of the

cap 11 centrally thereof so that the lower annular edge 14 thereof will extend slightly below and concentrically around the upper end of the tube 6. Thus, any oil forcefully ejected from the top end of the tube 6 will engage the underside of the cap 11 within the collar 13 and be guided downwardly to drip off the annular edge 14 back into the main chamber of the cup.

- 10 From the foregoing description, taken in connection with the accompanying drawing, it is thought that the novel details of construction, manner of use and the advantages of my invention will be readily apparent to those skilled in the art to which the invention relates.

What I claim is:

In an oil cup of the class described, where-
in is embodied a casing, a filter-feed means
in the casing, and a free passage oil tube 20
passing through the filter feed means and
having its upper end extended approxi-
mately to the top of the cup; a closure cap
spring hinge connected at one side to the
cup and which has a downturned flange sur-
rounding the cup and an annular collar ex-
tended downwardly from the underside of
the cap and surrounding the upper end of
the tube, the lower edge thereof projecting
slightly below the said tube end. 25

FRANK EIDEN.
